ART OF CRACKING AND COKEING HYDROCARBON OILS

Filed Feb. 18, 1929

UNITED STATES PATENT OFFICE

HARRY L. PELZER, OF HIGHLAND, INDIANA, ASSIGNOR TO SINCLAIR REFINING COMPANY, OF NEW YORK, N. Y., A CORPORATION OF MAINE

ART OF CRACKING AND COKING HYDROCARBON OILS

Application filed February 18, 1929. Serial No. 340,996.

This invention relates to improvements in the combined vapor phase cracking of oils, such as gas oil or kerosene stocks, for the production of lower boiling oils, such as gasoline, and the coking of heavy oils, such as crudes, topped crudes, flux oils, other residual oils and the like. The combined operation of the invention is of special application in the handling of crude stocks or residual stocks the handling of which usually involves difficulties due to corrosion or the products of which are unusually refractory with respect to the usual refining operations, because of the character or quantity of sulfur compounds in the stock, for example; but, as will appear, the invention is, in certain aspects, of more general application.

According to this invention, the hot vapor mixture from a vapor phase cracking operation, while still at high temperature, is passed in intimate contact with a liquid oil mixture to be reduced to coke in a receptacle, a horizontal or vertical drum for example, adapted to receive an accumulating charge of coke and this liquid oil mixture is coked in this receptacle by the heat of the hot vapor mixture from the vapor phase cracking operation, the hot vapor mixture from the coking receptacle, including vapors formed in the coking operation as well as vapors from the vapor phase cracking operation, is discharged into and beneath the surface of a liquid body of oil in a separate receptacle, a drum with provision for the maintenance of this liquid body for example, the stock to be reduced to coke is supplied to this liquid body in the separate receptacle, and the oil mixture, constituting the liquid body in the separate receptacle, is supplied from the separate receptacle to the coking receptacle there to be reduced to coke. The vapor mixture from the separate receptacle, including vapors from the vapor phase cracking operation, vapors formed in the coking operation and any vapors separated from the stock supplied to the liquid body therein, is discharged to suitable condensing or fractionating and condensing or other recovery apparatus. The coke product formed in the coking receptacle

is periodically discharged therefrom. The hot vapor mixture from the vapor phase cracking operation is, with advantage, introduced into the coking receptacle before its temperature falls below 950° F., or better 1050° F., and usually it is, with advantage, introduced into the coking receptacle at the maximum possible temperature. The coking operation is promoted by maintaining intimate and distributed contact between the hot vapor mixture from the vapor phase cracking operation and the stock to be reduced to coke in the coking receptacle; the hot vapor mixture may be introduced into the coking receptacle in fine streams at a number of points or the stock may be sprayed into the coking receptacle or both of these expedients may be utilized, for example. The maintenance of the necessary intimate contact between vapors and liquid in the coking operation, however, involves entrainment in the vapor mixture discharged from the coking receptacle of oily or tarry material, apparently in mist-like form. Such entrained material is separated from the hot vapor mixture discharged from the coking receptacle in the scrubbing operation to which this vapor mixture is subjected in the liquid oil body into which it is discharged. This scrubbing operation is promoted by maintaining the liquid body at a temperature not exceeding 800° F., or better 750° F. By supplying the stock to be coked to this liquid body, this stock is preheated before introduction into the coking receptacle and it is also made to serve, in an advantageous way, as a scrubbing medium for the separation of entrained material from the hot vapor mixture discharged from the coking receptacle and as a medium for returning such separated entrained material to the coking receptacle. Referring to the vapor phase cracking operation proper, the apparatus or the precise manner in which it is carried out is not important so long as the hot products of the operation are discharged therefrom at temperatures upwards of 950-1050° F. The coking operation, however, may be promoted by supplying a charging stock of limited boiling range to the vapor phase cracking opera-

tion; the charging stock supplied to the vapor phase cracking operation in the combined operation of the invention is, with advantage, a stock of which 70% boils off within a range not substantially exceeding 5 30° F. under atmospheric pressure.

The invention will be further described in connection with the accompanying drawing which illustrates, diagrammatically and conventionally, one form of apparatus, in elevation and partly in section with parts broken away, adapted for carrying out the invention, but it is intended and will be understood that the invention can be carried 10 out in other and different forms of apparatus and that this further description is intended as exemplification of the invention.

Referring to the drawing, in carrying out the invention in the apparatus illustrated, 15 the hot vapor mixture from the vapor phase cracking operation carried out in the heater 1, without substantial cooling, is introduced into the coking receptacle 2 in which it is passed in intimate contact with a liquid oil mixture to be coked supplied from a liquid oil 20 body of oil maintained in the lower end of tower 3, a separate receptacle, through connection 4 by means of hot-oil pump 5 and this oil mixture is thereby coked in receptacle 2, 25 the hot vapor mixture from the coking receptacle 2 is discharged into and beneath the surface of the liquid body of oil maintained in the lower end of tower 3, the oil to be reduced to coke is supplied to this liquid oil 30 body through connection 6, the resulting liquid oil mixture is supplied from this liquid body to the coking receptacle 2, as noted, the resulting vapor mixture is discharged from the upper end of tower 3 through connection 35 7, and the coke product is periodically discharged from the coking receptacle 2.

The vapor phase cracking operation proper may be carried out, for example, as described in application Serial No. 198,621, filed June 45 13, 1927, by me, and the hot vapor mixture from the digesting drums discharged directly into the coking receptacle, or the digesting drums may be omitted and the hot vapor mixture from the heater proper discharged directly 50 into the coking receptacle. In the combined operation of the invention, the coking operation subjects the hot vapor mixture from the vapor phase cracking operation to what might be termed a period of digestion. 55 In the apparatus illustrated, the vapor phase cracking operation proper is carried out in the heater 1 comprising two groups of series connected heating tubes arranged in the heating flue of a furnace 8, the oil flowing first 60 through one of the groups of heating tubes counter-current to the cooler heating gases and then through the other group of heating tubes concurrent to the hotter heating gases, a fan 9 for circulating the heating gases 65 through the heating flue, ducts 10 provided

with dampers as shown for recirculating part of the heating gases through the heating flue and for discharging part of the heating gases to the stack 11, a fan 12 and a preheater 13 arranged in the stack 11 for supplying pre-heated air for combustion to the firebox 14 of the furnace 8. Oil is supplied to the heater 1 through connection 15 and the hot oil products of the vapor phase cracking operation carried out therein are discharged through 70 connection 16.

The coking operation proper may be carried out, for example, in a horizontal or vertical drum with suitable means, removable heads or the like, for the discharge of the coke 75 product formed and deposited in the coking receptacle. In general, a vertical coking drum is more easily cleaned and a horizontal coking drum, excepting for special operating conditions, yields denser and more coherent 80 coke. For example, the coking operation may be carried out in a drum 5' in diameter and 20' high (vertically arranged) or in a drum 9' in diameter and 30' long (horizontally arranged); in the vertical drum the hot vapor mixture from the vapor phase cracking operation may be introduced through a single 85 inlet or through a number of inlets in the bottom or in the side walls near the bottom and in the horizontal drum the hot vapor mixture 90 from the vapor phase cracking operation may be introduced through $\frac{3}{4}$ " holes on 18" centers in the lower side of a 4" pipe arranged longitudinally and near the bottom of the drum. In the apparatus illustrated, the coking operation proper is carried out in the 95 drum 2. The hot vapor mixture from the heater 1 is discharged into the lower end of the coking drum through connections 16 and 17 and the hot vapor mixture from the coking 100 operation is discharged from the upper end of the coking drum through connection 18. A by-pass 19 is provided to permit the coking drum to be cut out, for cleaning and discharge of coke, without interrupting the 105 vapor phase cracking operation. The coke is discharged by removing the upper and lower heads of the coking drum. The oil mixture to be coked is sprayed into the top of the coking drum through connection 4.

Connections 20, 21 and 22 are provided for supplying steam to the heater 1, the lower end of the coking drum 2 and the lower end of the scrubbing tower 3, respectively, and condenser 23 is provided for use when steaming out the coking drum 2. Steam may be supplied to the heater 1 during the initial period of operation or during regular operation. Steam may be supplied to the coking 110 drum 2 during the initial period of operation, for example to assist in heating the coking drum to operating temperatures, during regular operation, or during the final period of operation, for example to assist in 115 drying the coke product. Steam may be sup- 120 125 130

plied to the scrubbing tower 3 during the initial period of operation or during regular operation, for example to assist in stripping the oil mixture constituting the liquid body in the lower end of the scrubbing tower of vaporizable constituents.

The scrubbing operation proper may be carried out in any suitable receptacle providing for the maintenance of a liquid body of oil and for the discharge of the hot vapor mixture from the coking operation into and beneath the surface of this liquid body so as to subject the hot vapor mixture to a thorough scrubbing. Means for refluxing very high boiling constituents of the vapor mixture escaping from the liquid oil body in the scrubbing operation to this liquid oil body, as in the apparatus illustrated, may be provided with advantage but are not essential. In the apparatus illustrated, the scrubbing operation proper is carried out in the scrubbing tower 3. The hot vapor mixture from the coking drum 2 is introduced into and beneath the surface of a liquid body of oil maintained in the lower end of this scrubbing tower through a normally submerged inlet connection 24. The oil stock to be reduced to coke is supplied to this liquid body through connection 6 and the resulting oil mixture is discharged through connection 25, the rates of supply and discharge being regulated to maintain the necessary liquid body. For example, a sufficient liquid body may be maintained in the lower end of tower 3 to submerge the end of the inlet connection 4' or thereabout. The liquid oil mixture to be coked is pumped from the liquid body in the lower end of tower 3 through connection 4 by means of hot-oil pump 5 into the coking drum. The particular type of hot-oil pump illustrated, that designated 5 and also that designated 26, is described in more detail in application Serial No. 197,209, filed June 7, 1927, by Thomas de C. Tifft. Any excess of this oil mixture is discharged through connection 27 and cooler 28 to storage. In the scrubbing apparatus illustrated, a number of fractionating baffles or plates are arranged in the upper part of the tower 3. Control of the scrubbing operation carried out in this tower may be supplemented by the regulated introduction, through connection 29, of a suitable refluxing medium. For example, a part of one or more oil fractions subsequently condensed in the operation may be supplied to the upper end of tower 3 through connections 30, 31 or 32, connection 33 and connection 29 by means of pump 34 as a refluxing medium, or a similar oil fraction from some other source may be supplied through connection 35 as a refluxing medium.

In the apparatus illustrated, fractionating tower 39 is provided for the separation of one or two intermediate oil fractions, if desired, and fractionating tower 40 is provided

for the separation or preparation of a charging stock for the vapor phase cracking operation, if desired, or for the direct production of a distillate product, gasoline for example, of the desired boiling range, if desired. Each of the towers 39 and 40 are provided with a number of fractionating baffles or plates; these towers may, for example, be of conventional "bubble" tower construction. Condensate is discharged from tower 40 through connection 41, and condensate is discharged from tower 39 through connection 42, or an additional condensate fraction may also be discharged from tower 39 from an intermediate point through connection 43. The vapor mixture escaping from the upper end of the scrubbing tower 3 is introduced either into the lower end of fractionating tower 39 through connections 7 and 44 or into the lower end of fractionating tower 40 through connections 7, 45 or 46, connection 45 being a by-pass around tower 39. The vapor mixture escaping from the upper end of the fractionating tower 39, when this tower is included in the operation, is introduced into the lower end of fractionating tower 40 through connection 46. The vapor mixture introduced into tower 40 through connection 46 may be introduced either into the lowermost part of the tower through connection 47 or into the tower at an intermediate point in the lower part through connection 48 to provide for stripping of the condensate separated in this fractionating tower. A pair of reflux condensers, 50 and 51, 52 and 53, are provided in connection with fractionating towers 39 and 40, respectively, to provide control of the fractionating operations carried out in these towers. These fractionating operations may be controlled by regulated refluxing of the vapor mixtures escaping through these reflux condensers, or by the regulated introduction of refluxing media through connections 49 and 54, or by both of these means. Water or some other extraneous cooling medium may be used to control condensation in reflux condensers 51 and 53, supplied through connection 55 and discharged through connection 56. The oil to be reduced to coke, for example, or part of it, may be used to control condensation in reflux condensers 50 and 52, supplied through connection 57 and discharged through connection 58, such oil at the same time thereby being preheated. Either or both an extraneous cooling medium and a stock cooling medium may be used in either or in both pairs of reflux condensers in the same operation. When both of the reflux condensers 51 and 53 are used, the extraneous cooling medium may be passed through them in parallel or first through 53 and then through 51 by means of the connections shown, and similarly, when both of the reflux condensers 50 and 52 are used, the stock cooling medium may be passed

through them in parallel or first through 52 and then through 50. A part of one or more oil fractions condensed in tower 39 or in tower 40 may be supplied to the upper end of 5 tower 39 through connections 30, 31 or 32, connection 36 and connection 49 by means of pump 37 as a refluxing medium, or a similar oil fraction from some other source may be supplied through connection 38 as a refluxing medium. A part of the distillate product may be supplied to the upper end of tower 40 through connections 59 and 54 by means of pump 60 as a refluxing medium, or a similar oil fraction from some other source 10 may be supplied through connection 61 as a refluxing medium. Any condensate or condensates discharged from fractionating tower 39 not returned as a refluxing medium, and any condensate discharged from fractionating tower 40, either before or after 15 passing through heat exchanger 62, not returned as a refluxing medium or not supplied to the vapor phase cracking operation, are discharged through coolers 63, 64 and 65 and 20 connections 66, 67 and 68 to storage. 25

In the apparatus illustrated, the vapor mixture escaping from the fractionating tower 40 through connection 69 is discharged to the condenser 70, either directly through 20 connection 71 or through the refining tower 72 through connections 73 and 74. When the refining tower 72 is included in the operation, the vapor mixture may be subjected to refining treatment therein, for example by passage through an adsorptive catalyst such as 25 fuller's earth. High boiling material separated in the refining tower, polymers produced by the action of an adsorptive catalyst for example, may be discharged through 30 connection 75 or returned to the operation, through connection 76, with the stock to be coked. The condenser 70 is arranged to discharge into receiver and separator 77. Condensate is discharged from receiver 77 35 through connections 78 and 79 and unden-sed vapors and gases are discharged through connection 80.

In the apparatus illustrated, the charging stock supplied to the vapor phase cracking 50 operation through connection 15 may comprise either a raw stock supplied through connection 81 by means of pump 82, or a condensate from tower 40 or a condensate mixture from tower 40 including unvaporized 55 constituents of a refluxing medium introduced through connection 54 or connections 54 and 61 (supplied through connection 83 by means of pump 26) or a condensate or condensate mixture from tower 40 together with 60 a raw stock supplied through connection 84, or a mixture of any two or more of the foregoing. All or part of the condensate or condensate mixture discharged through connection 41, or all or part of the condensate or condensate mixture discharged through connec- 65

tion 41 and supplied to the vapor phase cracking operation, may be passed through the heat exchanger 62.

In the apparatus illustrated, the oil stock to be reduced to coke supplied to the liquid oil body in the lower end of tower 3 and thence to the coking drum 2 may either be supplied, or in part supplied, to this liquid oil body directly through connections 85, 86, 87, 88 and 6 by means of pump 89, or be supplied, or in part supplied, through connection 86, heat exchanger 62 and connections 90, 88 and 6, or be supplied, or in part supplied, through connections 86, 87 and 57, either or both reflux condensers 50 and 52 and connections 58 and 6, or be supplied, or in part supplied, through connection 86, heat exchanger 62, connections 90 and 57, either or both reflux condensers 50 and 52 and connections 58 and 6, or through any two or more of these paths. To the extent that this stock is passed through heat exchanger 62 or reflux condensers 50 and 52, it is thereby preheated.

In the apparatus illustrated, the coking drum 2, the towers 3, 39 and 40, the vapor lines between them and between the heater 1 and the coking drum, the connections 41 and 83, the connections 25 and 4 and the connections 90, 88, 57, 58 and 6 are, with advantage, lagged or thermally insulated.

A specific example of an operation embodying the invention as carried out in apparatus of the type illustrated will further exemplify the invention: Fires are started and the heating furnace 8 is brought to operating temperatures while circulating steam through the heater 1 and the coking drum 2. When the coking drum temperature reaches about 300° F., the circulation of gas oil instead of steam through the heater 1 is started; a raw gas oil is supplied to the heater until sufficient condensate has accumulated in tower 40 to supply the heater from this source. When the circulation of oil through the heater is started, topped crude is pumped into the lower end of tower 3 through connection 6 at a rate regulated to maintain the temperature of the liquid body therein in the neighborhood of 700° F. The resulting oil mixture is pumped from the lower end of tower 3 at a rate regulated to maintain a liquid oil body therein submerging the inlet connection 24 the desired depth; this oil mixture is pumped to storage until the system has reached uniform operating conditions and it is then pumped into the coking drum 2 through connection 4. During regular operation, the furnace operation is regulated so that the hot vapor mixture from the vapor phase cracking operation is discharged through connection 16 at a temperature in the neighborhood of 1100-1120° F., the temperature of the liquid body in the lower end of tower 3 is maintained in the neighborhood of 700° F., and the temperature of the vapor

mixture discharged from the coking drum into this liquid body may approximate 900-1000° F. The topped crude supplied to the liquid body in the lower end of tower 3 through connection 6 is passed through the heat exchanger 62 and then through reflux condenser 50 on its way to this liquid body. No other refluxing medium, direct or indirect is used in tower 39. Heavy gas oil, a condensate from tower 39 for example, is supplied to the upper end of tower 3 at a rate regulated to maintain the vapor mixture escaping through connection 7 at a temperature in the neighborhood of 700° F. The 10 condensate or condensate from tower 39, excepting such as is supplied to the upper end of tower 3 as a refluxing medium, is pumped to storage. Water is circulated through reflux condenser 53 at a rate regulated to maintain the vapor mixture escaping through connections 69 and 71 directly to condenser 70 such that not less than 90% of the resulting distillate product boils off up to 392° F. under atmospheric pressure. The condensate 15 from tower 40, together with light gas oil supplied through connection 84 at a rate regulated to maintain a substantially constant volume of condensate in the lower end of tower 40, is pumped through the heater 1. When a charge of coke has accumulated in the coking drum 2, the oil mixture from the liquid body in the lower end of tower 3 is again pumped to storage instead of to the coking drum. The hot vapor mixture from 20 the heater 1 is passed through the heater for a further period long enough to insure drying of the coke product, 8 hours for example, and this vapor mixture is then by-passed to the tower 3, the coking drum being then steamed out and the charge of coke removed. As soon as the coking drum has been cleaned, it is cut back in again and the coking operation is resumed. A tar resulting from a cracking operation, a pressure cracking still tar for example, may, with advantage, be mixed with the stock to be reduced to coke and this mixture supplied to the operation, as described in 25 application Serial No. 345,892, filed March 9, 1929, by George R. Lord. However, in carrying out this invention, some tar produced in the vapor phase cracking operation is separated from the hot vapor mixture subjected to the scrubbing operation in the oil mixture supplied to the coking operation and, probably, some tar produced in the vapor phase cracking operation is separated from the hot vapor mixture in the coking operation itself. In carrying out the present invention, the 30 stock supplied to the vapor phase cracking operation proper may consist exclusively of, or may comprise in large part, oil components vaporized from the stock to be reduced to coke in the coking operation proper or in the scrubbing operation and subsequently

separated from the vapor mixture including the vapors of the desired distillate product, for example by condensation in tower 40 in the apparatus illustrated, before condensation of the distillate product. 70

I claim:

1. In a combined oil vapor phase cracking and coking operation, the improvement which comprises vaporizing and cracking oil in the vapor phase, passing the hot vapor mixture 75 from the vapor phase cracking operation, before the temperature of the said vapor mixture falls below 950° F., in intimate contact with a heavy hydrocarbon liquid oil mixture to be reduced to coke in a receptacle adapted to receive an accumulating charge of coke and thereby coking said oil mixture in said receptacle, discharging the hot vapor mixture from the said coking receptacle into and beneath the surface of a liquid 80 body of oil in a separate receptacle, supplying the oil to be reduced to coke to the said liquid body in the said separate receptacle and supplying the resulting liquid oil mixture from the liquid body 85 in the said separate receptacle to the said coking receptacle, discharging a vapor mixture from the said separate receptacle and periodically discharging a coke product from the said coking receptacle. 90

2. In a combined oil vapor phase cracking and coking operation, the improvement which comprises vaporizing and cracking oil in the vapor phase passing the hot vapor mixture from the vapor phase cracking operation, before the temperature of the said vapor mixture falls below 1050° F., in intimate contact with a heavy hydrocarbon liquid oil mixture to be reduced to coke in a receptacle adapted to receive an accumulating charge of coke and thereby coking said oil mixture in said receptacle, discharging the hot vapor mixture from the said coking receptacle into and beneath the surface of a liquid body of oil in a separate receptacle, supplying the oil to be reduced to coke to the said liquid body in the said separate receptacle and supplying the resulting liquid oil mixture from the liquid body in the said separate receptacle to the said coking receptacle, discharging a vapor mixture from the said separate receptacle and periodically discharging a coke product from the said coking receptacle. 100

3. In a combined oil vapor phase cracking and coking operation, the improvement which comprises vaporizing and cracking oil in the vapor phase passing the hot vapor mixture from the vapor phase cracking operation, before the temperature of the said vapor mixture falls below 950° F., in intimate contact with a heavy hydrocarbon liquid oil mixture to be reduced to coke in a receptacle adapted to receive an accumulating charge of coke and thereby coking said oil mixture in said receptacle, discharging the hot vapor 110

115

120

125

130

- 5 mixture from the said coking receptacle into and beneath the surface of a liquid body of oil maintained at a temperature not exceeding 800° F. in a separate receptacle, supplying the oil to be reduced to coke to the said liquid body in the said separate receptacle and supplying the resulting liquid oil mixture from the liquid body in the said separate receptacle to the said coking receptacle, discharging a vapor mixture from the said separate receptacle and periodically discharging a coke product from the said coking receptacle.
- 10 4. In a combined oil vapor phase cracking and coking operation, the improvement which comprises vaporizing and cracking oil in the vapor phase passing the hot vapor mixture from the vapor phase cracking operation, before the temperature of the said vapor mixture falls below 950° F., in intimate contact with a heavy hydrocarbon liquid oil mixture to be reduced to coke in a receptacle adapted to receive an accumulating charge of coke and thereby coking said oil mixture in said receptacle, discharging the hot vapor mixture from the said coking receptacle into and beneath the surface of a liquid body of oil maintained at a temperature not exceeding 750° F. in a separate receptacle, supplying the oil to be reduced to coke to the said liquid body in the said separate receptacle and supplying the resulting liquid oil mixture from the liquid body in the said separate receptacle to the said coking receptacle, discharging a vapor mixture from the said separate receptacle and periodically discharging a coke product from the said coking receptacle.
- 15 5. In a combined oil vapor phase cracking and coking operation, the improvement which comprises vaporizing and cracking oil in the vapor phase supplying a stock of which 70% boils off within a range not substantially exceeding 30° F. under atmospheric pressure to a vapor phase cracking operation, passing the hot vapor mixture from the vapor phase cracking operation, before the temperature of the said vapor mixture falls below 950° F., in intimate contact with a heavy hydrocarbon liquid oil mixture to be reduced to coke in a receptacle adapted to receive an accumulating charge of coke and thereby coking said oil mixture in said receptacle, discharging the hot vapor mixture from the said coking receptacle into and beneath the surface of a liquid body of oil in a separate receptacle, supplying the oil to be reduced to coke to the said liquid body in the said separate receptacle and supplying the resulting liquid oil mixture from the liquid body in the said separate receptacle to the coking receptacle, discharging a vapor mixture from the said separate receptacle and periodically discharging a coke product from the said coking receptacle.
- 20 6. In a combined oil cracking and coking

operation, the improvement which comprises passing an oil to be cracked through a heating conduit and heating this oil to a high cracking temperature therein, passing the hot oil products from the heating conduit, before the temperature of said hot oil products falls below 950° F., in intimate contact with a heavy hydrocarbon oil mixture to be reduced to coke in a receptacle adapted to receive an accumulating charge of coke and thereby coking said oil mixture in said receptacle, discharging the hot vapor mixture from said coking receptacle into and beneath the surface of a liquid body of oil in a separate receptacle, supplying the oil to be reduced to coke to the said liquid body in the said separate receptacle, supplying the oil to be reduced to coke to the said liquid body in the said separate receptacle and supplying the resulting liquid oil mixture from the liquid body in the said separate receptacle to the coking receptacle, discharging a vapor mixture from the said separate receptacle and periodically discharging a coke product from the said coking receptacle.

25 7. In a combined oil cracking and coking operation, the improvement which comprises passing an oil to be cracked through a heating conduit and heating this oil to a high cracking temperature therein, passing the hot oil products from the heating conduit, before the temperature of said hot oil products falls below 1050° F., in intimate contact with a heavy hydrocarbon oil mixture to be reduced to coke in a receptacle adapted to receive an accumulating charge of coke and thereby coking said oil mixture in said receptacle, discharging the hot vapor mixture from said coking receptacle into and beneath the surface of a liquid body of oil in a separate receptacle, supplying the oil to be reduced to coke to the said liquid body in the said separate receptacle and supplying the resulting liquid oil mixture from the liquid body in the said separate receptacle to the coking receptacle, discharging a vapor mixture from the said separate receptacle and periodically discharging a coke product from the said coking receptacle.

30 8. In a combined oil cracking and coking operation, the improvement which comprises passing an oil to be cracked through a heating conduit and heating this oil to a high cracking temperature therein, passing the hot oil products from the heating conduit, before the temperature of said hot oil products falls below 950° F., in intimate contact with a heavy hydrocarbon oil mixture to be reduced to coke in a receptacle adapted to receive an accumulating charge of coke and thereby coking said oil mixture in said receptacle, discharging the hot vapor mixture from said coking receptacle into and beneath the surface of a liquid body of oil maintained at a temperature not exceeding 800° F. in a separate receptacle, supplying the oil to be reduced to coke to the said liquid body in the

said separated receptacle and supplying the resulting liquid oil mixture from the liquid body in the said separate receptacle to the coking receptacle, discharging a vapor mixture from the said separate receptacle and periodically discharging a coke product from the said coking receptacle.

9. In a combined oil cracking and coking operation, the improvement which comprises passing an oil to be cracked through a heating conduit and heating this oil to a high cracking temperature therein, passing the hot oil products from the heating conduit, before the temperature of said hot oil products falls below 950° F., in intimate contact with a heavy hydrocarbon oil mixture to be reduced to coke in a receptacle adapted to receive an accumulating charge of coke and thereby coking said oil mixture in said receptacle, discharging the hot vapor mixture from said coking receptacle into and beneath the surface of a liquid body of oil maintained at a temperature not exceeding 750° F. in a separate receptacle, supplying the oil to be reduced to coke to the said liquid body in the said separate receptacle and supplying the resulting liquid oil mixture from the liquid body in the said separate receptacle to the coking receptacle, discharging a vapor mixture from the said separate receptacle and periodically discharging a coke product from the said coking receptacle.

10. In a combined oil cracking and coking operation, the improvement which comprises passing a hydrocarbon oil stock of which 70% boils off within a range not substantially exceeding 30° F. under atmospheric pressure through a heating conduit and heating this oil to a high cracking temperature therein, passing the hot oil products from the heating conduit, before the temperature of said hot oil products falls below 950° F., in intimate contact with a heavy hydrocarbon oil mixture to be reduced to coke in a receptacle adapted to receive an accumulating charge of coke and thereby coking said oil mixture in said receptacle, discharging the hot vapor mixture from said coking receptacle into and beneath the surface of a liquid body of oil in a separate receptacle, supplying the oil to be reduced to coke to the said liquid body in the said separate receptacle and supplying the resulting liquid oil mixture from the liquid body in the said separate receptacle to the coking receptacle, discharging a vapor mixture from the said separate receptacle and periodically discharging a coke product from the said coking receptacle.

In testimony whereof I affix my signature.
HARRY L. PELZER.
